UNITED STATES PATENT OFFICE.

JOSEPH M. MERROW, OF MANSFIELD, CONNECTICUT.

TAKE-UP FOR SEWING-MACHINES.

SPECIFICATION forming part of Letters Patent No. 570,136, dated October 27, 1896.

Application filed January 11, 1894. Renewed September 25, 1896. Serial No. 607,002. (No model.)

To all whom it may concern:

Be it known that I, JOSEPH M. MERROW, of Merrow, in the town of Mansfield, county of Tolland, and State of Connecticut, have invented certain new and useful improvements in Take-Ups for Sewing-Machines; and I do hereby declare the following to be a full, clear, and exact description of the same, reference being had to the accompanying drawings, forming a part of this specification, and to the figures and letters of reference marked thereon.

My present invention relates particularly to that class of sewing-machines which form a double chain-stitch. In this class of machines the reciprocating needle is used to carry a thread through the fabric, and a reciprocating looper provided with another thread is used to enchain or interloop the needle-thread below the fabric and the looper-thread to produce the double chain-stitch, which is commonly designated generically as the "Grover & Baker" stitch. In order to produce this stitch in its best estate, it is necessary that the looper-thread should be properly taken up and let out, so that it will not be too loose at times or too tight at other times, and the object of this invention is to accomplish such purposes.

Throughout the drawings forming a part of this specification similar letters of reference indicate like parts.

Figure 1 is a front elevation of a double-chain sewing-machine provided with my new take-up apparatus. Fig. 2 is a detached view of a portion of the machine, showing a side elevation of the take-up devices.

A indicates the frame of the machine and serves as a support for the working parts. B indicates the needle-lever; C, its stud or support; D, the connecting-rod; E, the eccentric and hand-wheel; F, the main shaft; G, the looper-carrier; H, the looper; I, the looper-driving rod; J, the needle-bar; K, the needle; L, the presser-foot; M, the feed, and N the tension.

As is common in double-chain sewing-machines, I prefer to provide this machine with two sets of tensions, one for each of the threads, and the tension-disks for the looper-thread may be placed upon the same stud O, one set being upon the front side of the pro-

jection a of the frame and the other set being upon the rear side of the said projection, the stud O passing through and being secured to the said projection a. It is not necessary, however, that the looper-thread should always be provided with the usual tensions, as will hereinafter be explained.

The parts hereinabove specifically indicated are common in the well-known type of sewing-machines, and their operation is so well understood by all familiar with the art that I deem it unnecessary to further explain their relations and operations.

1 indicates the looper-thread take-up cam; 2, the balance of said cam; 3, the thread-guide, adjustably secured to the looper-driving rod I.

4 indicates the stationary looper-thread guide adjustably secured to its support 5, which latter is movably secured to the frame of the machine by means of the screw 6 and is held in position by means of the friction-disk 7.

The needle-thread P passes through the tension and take-up devices in the usual manner. The looper-thread 8 may pass through the tensions, as usual, and thence in any convenient course through the stationary thread-guide 4, thence around the periphery of the take-up cam 1, through the thread-guide 3, carried by the looper-driving-rod I, and thence to the looper.

The periphery of the cam 1 is made of such form as to take up and let out the looper-thread to correspond with similar variations in the looper-thread caused by the reciprocations of the looper. The arrow upon the cam 1 in Fig. 2 indicates the direction of the revolutions of the said cam, and the arrow above the looper-thread in the same figure indicates the direction in which the looper-thread will be carried or fed along as it is enchainged or taken up in the production of the stitches. The periphery of the cam 1, as it revolves in the direction contrary to the feeding of the looper-thread, causes a slight tension on the said looper-thread in addition to its action as a take-up on account of the friction of the said thread upon the periphery of the said cam, and this slight tension is sufficient to produce an elastic stitch without the employment of further tension apparatus. The amount of this friction varies with

the size of the cam 1 and the relative positions of the thread-guides. The thread-guide 4, being held to the frame of the machine by the friction-disk 7 and screw 6, may be swung 5 around away from the cam 1 to a sufficient distance to permit of easily passing the looper-thread through the thread-guide, after which the said thread-guide may be moved back to its proper position against its stop 9.

10 The brush 10 is placed so that it will press slightly against the greater portion of the cam 1, so that if the looper-thread in breaking should have at any time a tendency to wind around said cam it will be caught by the 15 brush instead of being carried around the cam. The brush also acts to clear the cam from any lint, oil, or other matters which might collect thereon. As the machine is operated the looper-thread is held nearly in one 20 position as it passes through the eye or guide 4, but as the looper-driving rod 1 reciprocates longitudinally the looper-thread will be carried similarly by the thread-guide 3 and traverses more or less diagonally around a portion 25 of the periphery of the cam 1, with which it is in contact. In practice I find that it is preferable to make the irregular surfaces of the cam 1 substantially parallel with its axis of rotation, especially on account of the cost 30 of construction, which would be greater if irregularities are made in two or more planes.

I have herein shown the cam 1 and the counterbalance 2 as being integral and secured to the main shaft by means of a single 35 screw 11, but these two elements may be

made separate, or the counterbalance may be made in two or more separate pieces.

Having thus described my invention, what I claim as new is—

1. In a sewing-machine, such as described, 40 the combination of the looper, the longitudinally-reciprocating looper-driving rod, the revolving take-up cam engaging the thread, the thread-guide mounted upon the said driving-rod on one side the cam and the fixed 45 thread-guide located on the opposite side of the cam; substantially as described.

2. In a take-up mechanism such as described, the combination of a rotary take-up cam, a thread-guide, mounted upon a fixed 50 support on one side of said cam and a second thread-guide mounted upon a support reciprocating in a plane substantially parallel with the axis of the cam and the face of the latter; substantially as described. 55

3. In a machine, such as described, the combination with the needle, and its actuating mechanism and the reciprocating looper and its actuating mechanism including the driving-rod, of the driving-shaft, the take-up 60 cam secured to said shaft in position to engage the thread, the fixed thread-guide and the reciprocating thread-guide, the latter mounted upon the looper-driving rod, substantially as described.

JOSEPH M. MERROW.
